FLOCK CUTTING MACHINE

Irving Hinerfeld, New York, N. Y.

Application August 28, 1939, Serial No. 291,999

2 Claims. (Cl. 83—6)

This invention is a comminuting machine used in connection with fibrous materials, such as cotton, wool, leather, etc.

In operating upon such fibrous materials, particularly in the cutting thereof into minute lengths, such as are required for the making of fillers and other bulk material used in plastics and for the manufacture of artificial leathers, considerable difficulty has been encountered due to the tendency of such fibers to bunch or matt. Comminuting fibrous material is best accomplished through the employment of relatively rotary and stationary knives, but fibers tend to bulk or matt in such a way as to clog these knives or to place such excessive strains on the apparatus heretofore employed as to cause serious manufacturing problems. In, for example, the manufacture of flock where relatively short, substantially uniform lengths of fibre are desired, the bunching up or matting of the fibres has not only seriously interfered with the cutting, but has also tended to clog the cutters and not infrequently resulted in the stoppage of production or of breakage of the mechanical parts employed in this operation.

The object of the present invention is to provide a machine which will satisfactorily comminute fibrous material in a thoroughly efficient manner with absolute safety and with increased output of material of substantially uniform length.

The machine of this invention embodies a rotor carrying a plurality of knives adapted to be operated at high speed about a fixed axis, so that the several knives of the rotor may coact with stationary knives mounted on the rigid frame of the machine. One important feature of this invention consists in providing within such a machine a screen of novel construction whereby the material to be operated upon is maintained in the zone of the knives until it has been cut to the desired dimension. This screen consists, generally speaking, of a relatively fine wire cloth reinforced on both sides by piles of sheet metal having therein registering perforations of much larger size than the mesh of the cloth, so as to properly support the mesh as will be hereinafter more fully explained.

Another feature of the invention consists in passing through the machine, during the operation thereof, a current of air in sufficient volume and under sufficient velocity to efficiently cool the knives, to assist in the feed of material to the knives, and to also assist in the removal of the finished product from the machine; in short, to

maintain the machine at proper temperature and to facilitate the passage of the material therethrough. This current of air is moreover availed of to facilitate the collecting and packaging of the end product.

Another feature of the invention consists in the mounting of the stationary knives in such manner that they are positively locked in position by locking means capable of withstanding the unusually heavy shocks to which these knives are subjected during the cutting of fibrous material.

Features of the invention, other than those adverted to, will be apparent from the hereinafter detailed description and claims, when read in conjunction with the accompanying drawings.

The accompanying drawings illustrate one practical embodiment of the invention, but the construction shown therein is to be understood as illustrative, only, and not as defining the limits of the invention.

Figure 1 is a transverse section of a machine embodying this invention, this section being taken in the plane of the line I—I of Figure 2.

Figure 2 is a front view of the machine of Figure 1 showing certain parts broken away, so that their structure may be more clearly seen.

Figure 3 is a perspective view of one of two brackets employed in the machine for supporting the stationary knives.

Figure 4 is a perspective view of the screen.

Figure 5 is a fragmental section of a portion of the screen.

Figure 6 is a perspective view of a cradle which I employ to hold the screen normally in operative position with respect to the knives.

As shown in the accompanying drawings, the machine embodies two cast end plates 1 and 2 provided therein with aligned bearings 3 adapted to support the shaft 4 of a rotary cutter. The end plates are spaced apart at their bases by angle sections 5 positioned at the front and back of the machine and at their top portions by an elongated hollow casting 6 on which is superimposed a feed hopper 7. These parts are suitably bolted together, so as to collectively form the rigid frame of the machine.

Bolted between the end plates at the front and back of the machine are a pair of brackets, one of which is shown in detail in Figure 3. Each bracket comprises a rugged, rigid bar of metal 8 of substantially rectangular cross section and to the opposite ends of this bar are welded arcuate anchoring flanges 9. These are adapted to abut the inner faces of the end plates and be firmly bolted thereto to rigidly mount the bar 8.

which constitutes the stationary knife bar, in position. One of these brackets is positioned at the front and the other at the back of the machine and they collectively serve to provide two parallel rigid knife bars 8 positioned above the axis of the main shaft 4 and in inclined relation, as shown in Figure 1. Two knives are associated with each knife bar, the knives 10 being arranged in face abutting relation with the upper faces of the bars 8 and the knives 11 in corresponding relation to the lower faces of the bars. Both the bars and knives are perforated and locking bolts 12 extend through these perforations to lock the knives rigidly to the bars.

15 Each of the knives 10 and 11 is provided with transverse slots so that the blade can be adjusted in a direction normal to its cutting edge, but above each knife 10 and below each knife 11 are wide and thick cleats 13 and 14, respectively.

20 These cleats are in the form of plates which extend for the full length of the blade and are perforated, so that the bolts 12 can snugly pass therethrough and between the heads and nuts of the bolts and the plates 13 and 14 are positioned the usual washers 15. The use of plates 13 and 14 is of particular importance in this invention, for when I attempted to operate a machine without them, it was found that the shock of cutting fiber was so great that the washers 15 were deformed into the slots of the knives with the result that in some cases the knives were loosened while in other cases the heads of the locking bolts were broken off. I tried numerous expedients to overcome these difficulties, but was not successful in producing a satisfactory construction until I used the plates 13 and 14 to reinforce the structure and form a firm foundation for the nut and bolt heads. Since that time I have had no difficulty with the knife mountings.

25 The space between the end frames above the knives is enclosed at the front and back of the machine by aprons 17 held in place by screws 18 and provided with handles 19. The space between the end plates below the knife bars 8, at the front and back of the machine, are closed by similar aprons 20 held in place by screws 21 and having handles 22. As shown in Figures 1 and 2, the screws 21 pass through slots 23 in the aprons 20 and, when the screws are loosened, the aprons may be dropped down to release the flanges at their upper edges from engagement with the nuts of the locking bolts 12, so that the aprons can be lifted out to render the interior of the machine, below the knives, readily accessible.

30 Within the machine and mounted upon the shaft 4 is a rotary cutter head 24 to which is attached a series of cutting blades 25. Five of these blades are shown and the spacing of these knives and the stationary knives 10 and 11 is such that no two stationary and rotatable blades will come into cutting relation at the same time. The cutting is thus accomplished by the blades successively and the shock of this operation is thus distributed throughout 360 degrees of rotation of the cutter head.

35 Arranged below the rotary cutting head 24 is a coaxial screen, designated generally by the reference character 26. This screen is of three ply construction. The center ply consists of wire cloth 27 of a mesh appropriate to the requirements of the end product. For the manufacture of flock 60 to 150 mesh per inch is used and a steel or bronze cloth is preferred in this connection. Such a cloth, because of its fineness is fragile and I therefore reinforce it on both sides

by sheet metal which may be of strong and durable construction. 20 gauge thickness has been found to be effective. It is applied in the form of two sheets 28 and 29 facially contacting, respectively, with the concave and convex surfaces of the wire cloth and rivets 30 are passed through the entire assembly in closely spaced relation, so as to bind the laminations firmly together, so that they cannot be separated by material which would otherwise tend to work between them. 10 The inner plate 28 and the outer plate 29 are provided with juxtaposed perforations 31, which may conveniently be in the form of holes of $\frac{1}{2}$ " diameter. These holes must register with one another to preclude clogging of the screen. 15

The front and back edges of the screen are provided with metallic bindings 32 which are riveted in place and are shaped to seat against the under faces of the knives 11, as best shown in Figure 1, with the curvature of the screen, as 20 a whole, concentric with the cutter head. The screen is adapted to be normally held in place in this position by means of a cradle 33, shown in detail in Figure 6. This cradle is shaped to conform to the screen. It has substantially semi-circular ribs 34 joined at their free ends by rigidly attached longitudinal spacing bars 35 and across the bottom of this cradle is welded a channel section 36 with the channel facing downwardly. The channel of this section is adapted to receive 30 the square or hexagonal heads 37 of supporting struts 38 which extend downwardly through holes passing diametrically through a rock shaft 39, shown best in Figures 1 and 2. Rock shaft 39 is journaled at its opposite ends in the end plates 35 1 and 2 and is adapted to freely turn therein, except when locked against rotation by the studs when the heads 37 of the latter are in the channel section. The struts 38 are threaded and are adapted to receive adjusting nuts 40.

When the parts are in operative position, the adjusting nuts are screwed down tightly against the rock shaft 39, thereby elevating the heads 37 of these studs into the channel section 36 of the cradle, so that the cradle is forced upwardly and seats the bindings 32 of the screen firmly against the lower knives with the ends of the screen beneath semi-circular conforming shoulders 2a cast in the inner faces of the end plates. As long as these adjusting nuts 40 are tight the 50 screen will be held in this position and two or three of these studs are employed to insure a holding of the cradle and screen in place. When it is desired to remove the screen, the adjusting nuts 40 are backed off sufficiently to allow the 55 heads 37 of the studs to be withdrawn from the angle section 36 of the cradle and the rock shaft 39 is then oscillated to bring the studs into the dotted line position of Figure 1. This will release the cradle and screen, so that they may be 60 dropped down into the lower portion of the casing and, when one of the aprons 20 is removed, the screen and cradle can be lifted out bodily through the front or back of the machine as may be desired. 65

The bottom of the machine is closed by a plate 41 provided therein with an opening 42 with which registers the inlet end of an outlet duct 43. This duct includes an appropriate suction blower 44 adapted to discharge into a bell 45 to 70 which a sack 46 or other suitable container is adapted to be attached so as to receive the product of the machine.

The operation of the apparatus is as follows: Assuming, for example, that the machine is uti- 75

lized for the manufacture of flock, the apparatus is started by transmitting power to the main shaft 4 to cause rotation of the cutter head and at the same time power is applied to the suction blower 44. As a result the cutter head is rotated at high speed and there is also set up a rapidly moving current of air of considerable volume which enters the machine through the hopper 7, passes downwardly about the cutters and through the screen into the bottom of the machine from whence it passes through the outlet duct and through the blower 44 to the bell 45 and thence to the associated container 46.

Either of both the container and bell are of fabric or other foraminous material, so that the air can freely pass out through the walls thereof while any solid material entrained therein will remain in the bell or container. The material to be operated upon is now fed into the hopper. 20 Mill ends, fabric scrap, waste, and any other fibrous material adapted to be operated upon may be introduced. This material is immediately carried down into the cutting chamber of the machine where it is engaged by the rotary cutter head, and more particularly the cutters thereof, and carried into cutting relation with the knives 10 and 11 which shear the material as the rotary knives pass the stationary knives. The rotor is operated at high speed and the material introduced turns with the rotor and through centrifugal force, as well as the force of gravity, and is continuously subjected to the cutting and shearing operations of the knives for the purpose of rapidly reducing the material into fibres of 35 short length.

As the operation progresses, fibre divisions will result which are small enough to pass through the screen and more particularly through the wire cloth portion thereof and as such fine divisions are formed, they will pass through the screen and fall into the lower portion of the chamber of the machine. The efficient passage of these finely divided fibers through the mesh of the screen will be materially expedited by the current of air passing through the machine, and at the same time, said current of air will assist in the feed of further material into the machine, will preclude the throwing of material by the rotor out through the hopper, and will assist in 50 the agitation of the material in the cutting chamber and the separation of masses of fibre therein.

Concurrently air passing through the machine, as stated, will have a very marked cooling effect upon the knives and will preclude them from 55 overheating to a point at which the temper may be drawn. The maintenance of a cool condition in machines of this kind has long been a serious problem, but I have found that the circulation of air in considerable volume through the machine during the cutting operation is the solution of the problem and this constitutes an important phase of the present invention.

A further function of the air is to carry off the cut material as it leaves the screen and to 60 pass it through the outlet duct 43 to the container 46 in which it is either finally or preliminarily packaged.

Experience has shown that when air is passed 70 through the machine in the manner described, the output of the machine is greatly increased by immediately freeing from the cutting chamber or zone, all material that can pass through the screen. Consequently this material does not back

up at the screen and clog the apparatus. It is freed from the cutting chamber practically as soon as it is cut to sufficient size to pass through the screen.

In the manner described material is passed through the machine without danger to the machine parts or to workmen and in an unusually rapid manner. In fact the fibrous material is operated upon with great efficiency in this apparatus in spite of the dangerous character of such material and its tendency to bunch and matt.

The present invention has also been employed with success in comminuting rayon and similar materials and has also been found to give highly satisfactory results when so used.

The foregoing detailed description sets forth the invention in its preferred practical form, but the invention is to be understood as fully commensurate with the appended claims. 20

The comminuting of material by the use of stationary and cooperating rotating knives with coincident feed of the material to the knives by a current of air which cools the knives and facilitates the feed of the cut material through a 25 screen and thereafter passes it to and packs it within a container, constitutes a novel method forming part of this invention.

Having thus fully described the invention, what I claim as new and desire to secure by Letters 30 Patent is:

1. A comminuting apparatus comprising a casing having a main shaft extending therethrough, a rotary cutter head mounted on the main shaft and carrying cutter blades, relatively fixed cutter blades mounted on the casing in cooperative relation to the blades of the cutter head, a screen of substantially cylindrical form extending across the casing below the cutter head and substantially coaxial therewith, said screen having a 40 layer of fine mesh wire cloth interposed between sheet metal plates respectively provided with juxtaposed perforations and secured to one another through the wire cloth to retain the plates and cloth firmly in face abutting relation, a cradle 45 supporting said screen from below and substantially conforming to the shape thereof, a rock shaft extending across the casing below the cradle, and threaded studs supported by the rock shaft engaging with the cradle to support the 50 cradle and superimposed screen in cooperative relation with the rotary cutter head.

2. A flock cutting apparatus comprising a casing having a cutter shaft extending therethrough, a rotary cutter head mounted on said shaft and 55 carrying cutter blades, relatively fixed cutter blades mounted on the casing in cooperative relation to the blades of the cutter head, a screen of substantially semi-cylindrical form extending uninterruptedly across the casing below the cutter head and substantially coaxial therewith, a cradle supporting said screen from below and substantially conforming to the shape thereof, a rock shaft parallel to the cutter shaft and extending across the casing below the cradle and 60 beneath the longitudinal medial line thereof, and threaded studs supported by the rock shaft engaging with the cradle midway between its lateral edges to support the cradle and superimposed screen in cooperative relation with the rotary 65 cutter head.

IRVING HINERFELD.
